Harry W. Bowen.

ATTORNEY.

UNITED STATES PATENT OFFICE

RALPH H. RIDGEWAY, OF SPRINGFIELD, MASSACHUSETTS

HATBAND

Application filed March 6, 1929. Serial No. 344,713.

This invention relates to improvements in inner hat bands.

An object of the invention is to provide a hat band that is located on the inner surface 5 of a hat or cap for the purpose of affording a free and unrestricted circulation of the blood to the roots of the hair. It is generally understood that baldness is due to the pressure of the sweat band or interior band cutting off or partially preventing the free circulation of the blood to the roots of the hair.

The present invention, broadly considered, comprises an inner hat band that is formed with a series of elevations and depressions 15 for the purpose of preventing a continuous pressure of the band on the head of the wearer, particularly at the side or temples where the blood vessels are located.

These projections and depressions are 20 formed wedge-shaped; the depressions having narrow openings at their bottoms and wider spaces or openings at their tops, or upper ends. The band is designed to encircle the inner surface of the hat. The projections 25 are formed with wide lower ends and narrower upper ends. In general, the improvement comprises a member or attachment to the ordinary inner hat band, which band overlaps the continuous strip having the elevations and depressions, as will be fully described.

Referring to the drawings:

Fig. 1 is a transverse sectional view considered in a vertical plane passing through 35 the hat showing the improvement applied to its inner surface.

Fig. 2 is an enlarged detail sectional view showing a portion of the band and the hat.

Fig. 3 is a detail, developed view of a portion 40 of the continuous strip which is formed with the wedge-shaped elevations and depressions and a portion of the usual hat band.

Fig. 4 is a portion of the strip and the usual 45 sweat band assembled and illustrating the wavy condition of the band, when in use, and

Fig. 5 is a sectional view on the line 5—5 of Fig. 3.

Referring to the drawings in detail:

1 is a strip of suitable material, as pliable leather, which is formed with the wedge-

shaped elevations 2 and the wedge-shaped depressions 3. These elevations or projections are spaced from the lower edge 4 to provide a portion 5 for attaching the usual leather sweat band, indicated at 6. This band 55 is stitched, or otherwise secured, to the portion 5. The depressions 3, as shown, are wedge-shaped, their entrance or lower openings 7 being less than their upper outlet ends, indicated at 8. This is for the purpose of 60 permitting the blood to freely spread out in a fan-like manner, as shown by the arrows 9, when the hat is worn. The elevations 2 are wider at their lower edges, as indicated at 10, and more narrow at their top edges 11. 11 designates the stitches for securing the sweat 65 band 6 to the flexible leather strip 1 on the portion of the surface indicated at 5, and the stitches 12 are for securing the strip 1 to the lower inner edge of the body of the hat 70 12', adjacent the rim 12".

Referring to Fig. 4, the depressions 3 permit the sweat band 6 to bend slightly inward into these depressions when the hat is being worn, and elevations 2 are the portions that 75 rest against the head of the wearer, as indicated in Fig. 4 at 13. This results in the portion 14 opposite the depression 3, not resting against the head, thus affording free circulation for the blood.

It is understood that the improved hat or sweat band extends completely around the inner surface of the hat, which is indicated at 12'. The band 6 is folded upward, as 80 shown in Figs. 1 and 2.

From this description, it will be seen, I have provided an improvement in sweat or hat bands which are adapted to be attached to the usual hat construction, either felt or straw material, and one that does not materially obstruct or interfere with the free flow or circulation of the blood.

What I claim is:—

1. In a hat, an interior hat band comprising a continuous strip of flexible material, that is formed with spaced integral wedge-shaped elevations and depressions and having its lower edge thinner below the elevations, means for attaching the usual sweat band to the thin portion of said strip, below 95

the lower edges of the elevations and on the outer side of the strip, whereby these spaced series of elevations, when the band is turned upward, will provide bearing or contact points of the said band with the head of the wearer and the spaces between the projections will afford a free circulation of the blood to the roots of the hair, as described.

2. In a hat, an interior hat band comprising a continuous strip of flexible material, that is formed with wedge-shaped elevations, which are small in width at their tops and increasing in width toward the bottoms, and corresponding wedge-shaped depressions, which are large in width at their tops and decreasing in width toward the bottom and said strip being located between the crown of the hat and the usual hat band and attached to the latter, whereby these wedge-shaped spaced series of elevations will provide a series of progressively increasing unrestricted areas between the band and the head of the wearer for providing free circulation of the blood to the roots of the hair, as described.

In testimony, I have subscribed my name this 20th of February, 1929.

RALPH H. RIDGEWAY.
